FIG - 6

FIG - 7

FIG-8FIG-9FIG-10FIG - 13FIG - 14FIG - 15FIG. 1 is a left side, top and front perspective view of a cabinet for a stereo phonograph or similar article, showing one form of our new design with the hinged speaker cabinets in closed position;

FIG. 2 is a left side, top and front perspective view of the form shown in FIG. 1 with the hinged speaker cabinets in opened position;

FIG. 3 is a top plan view of the form shown in FIG. 1;

FIG. 4 is a bottom plan view of the form shown in FIG. 1;

FIG. 5 is a left side elevational view of the form shown in FIG. 1, the opposite side being substantially a mirror image thereof;

FIG. 6 is a left side, top and front perspective view of a cabinet for a stereo phonograph or similar article, showing a second form of our new design with the hinged speaker cabinets in closed position;

FIG. 7 is a left side, top and front perspective view of the form shown in FIG. 6 with the hinged speaker cabinets in opened position;

FIG. 8 is a top plan view of the form shown in FIG. 6;

FIG. 9 is a bottom plan view of the form shown in FIG. 6;

FIG. 10 is a left side elevational view of the form shown in FIG. 6, the opposite side being substantially a mirror image thereof;

FIG. 11 is a left side, top and front perspective view of a cabinet for a stereo phonograph or similar article, showing a third form of our new design with the hinged speaker cabinets in closed position; and

FIG. 12 is a left side, top and front perspective view of the form shown in FIG. 11 with the hinged speaker cabinets in opened position.

FIG. 13 is top plan view of the form shown in FIG. 11; FIG. 14 is a bottom plan view of the form shown in FIG. 11; and

FIG. 15 is a left side elevational view of the form shown in FIG. 11, the opposite side being substantially a mirror image thereof.

The back of each form, not shown, is a substantially flat, unornamented surface.

We claim:

The ornamental design for a cabinet for a stereo phonograph or similar article, substantially as shown and described.
